DESIGN FOR A COMBINATION CHAIR AND FURNITURE BASE

Charles V. Cowan, Beverly Hills, Calif.

Application November 17, 1944, Serial No. 116,405

Term of patent 14 years

(CL. D15—1)

To all whom it may concern:

Be it known that I, Charles V. Cowan, a citizen of the United States, residing at Beverly Hills, in the county of Los Angeles and State of California, have invented a new, original, and ornamental Design for Combination Chair and Furniture Base, of which the following is a specification, reference being had to the accompanying drawing, forming part thereof.

Fig. 1 is a side elevational view of a combination chair and furniture base showing my new design; and

Fig. 2 is a view taken at right angles to Fig. 1.

Fig. 3 is a side perspective view illustrating the device as it appears when it is used as a chair; while

Fig. 4 illustrates the device as it appears in the position when used as a pedestal.

I claim:

The ornamental design for a combination chair and furniture base, as shown and described.

CHARLES V. COWAN.
